[57] CLAIM

The ornamental design for a set of decals for socks, as shown and described.

DESCRIPTION

FIG. 1 is a front elevational view of the set of decals for socks showing our new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof; and,

FIG. 7 is an isometric view thereof, the broken line showing of a pair of socks being for environmental purposes only and forming no part of the claimed design.

The single decal is shown in FIG. 7 as an illustration of use. The remainder of the claimed design has been omitted for convenience of illustration.
